UNITED STATES PATENT OFFICE.

CHARLES S. LEWIS, OF ST. LOUIS, MISSOURI.

PUMP-PRIMING MECHANISM.

1,080,917.

Specification of Letters Patent. Patented Dec. 9, 1913.

Application filed October 26, 1912. Serial No. 727,880.

To all whom it may concern:

Be it known that I, CHARLES S. LEWIS, a citizen of the United States, residing at St. Louis, Missouri, have invented a certain 5 new and useful Improvement in Pump-Priming Mechanism, of which the following is a full, clear, and exact description, such as will enable others skilled in the art to which it appertains to make and use the 10 same.

This invention relates to devices that are used for supplying a liquid to the suction side of a centrifugal or rotary pump so as to prime the pump when it becomes air-bound.

One object of my invention is to provide a pump-priming apparatus or mechanism which is so designed that a quantity of liquid sufficient to prime the pump will be supplied to the suction side of the pump automatically whenever the pump becomes air-bound.

Another object is to provide a pump-priming apparatus which is so designed that 25 it will automatically remove the air in the supply line between the suction side of the pump and the supply of liquid to be pumped and thus cause said liquid to enter the suction side of the pump.

30 Another object is to provide an apparatus that is adapted to be arranged between a centrifugal or rotary pump and the supply line and which comprises means for reducing the pressure or creating a partial 35 vacuum in the supply line so as to start the flow of the liquid through said supply line when the pump is first set in operation or when the flow has been interrupted as, for example, by air having entered the supply line.

40 Another object is to provide an apparatus which makes it possible to use a centrifugal or rotary pump for exhausting air or gases from a line or closed vessel or for reducing 45 the pressure in same. And still another object is to provide a vacuum-producing apparatus consisting of two communicating chambers and a centrifugal pump arranged in such a manner that the pump will suck 50 charges of liquid out of one of said chambers intermittently and thus reduce the pressure or create a partial vacuum in said chamber and in the suction line that communicates with said chamber.

The figure of the drawing is a vertical 55 sectional view of an apparatus constructed in accordance with my invention.

Briefly described, my apparatus consists of two chambers, a centrifugal or rotary pump connected by means of a suction pipe 60 with one of said chambers and by means of a discharge pipe with the other chamber, and means for permitting a relatively lesser volume of liquid to flow from the chamber that communicates with the discharge pipe 65 of the pump into the chamber that communicates with the suction side of the pump than the volume that is drawn simultaneously from the lower chamber by the pump, thus causing a partial vacuum or diminution 70 of pressure in the chamber that communicates with the suction side of the pump, the liquid continuing to flow into said chamber from the other chamber and the pump drawing or sucking out the accumulated liquid from said chamber intermittently, a partial vacuum or diminution 75 of pressure resulting in said chamber each time the accumulated volume of liquid is withdrawn.

80 Referring to the drawing which illustrates the preferred form of my invention, A and B designate two chambers that communicate with the suction side and with the discharge side, respectively, of the centrifugal or rotary pump C with which the apparatus is used, and D designates a separate chamber preferably in the form of a conduit which communicates at one end with the chamber A and at its opposite end with a 85 supply pipe E through which liquid, gas or air is to be drawn. The cubical contents of the chamber B is preferably greater than the cubical contents of the chamber A, and said chamber B is arranged at a higher 90 level than the chamber A, preferably above same, as herein shown, so that the liquid in the chamber B will flow into the chamber A through a duct or orifice that establishes communication between said chambers. In the 100 preferred form of my invention, as herein shown, a bypass 1 leads from the lower end of the chamber B to the upper end of the chamber A, and a valve 2 is provided for regulating the flow of the liquid through 105 said bypass and cutting off the flow of the liquid under certain conditions, the stem 2 of said valve being provided with an ad-

justing nut 2^b. A pipe 3 which leads from the suction side of the pump C, projects into the lower chamber A and terminates a short distance from the bottom of said chamber, 5 the end of said pipe being curved downwardly and the pump C being so arranged with relation to said pipe that the intake of the pump is higher than the open lower end of the pipe 3. A pipe 4 leads from the discharge side of the pump C to the upper chamber B, and said chamber is provided at its upper end with a discharge orifice 5 with which a discharge pipe 6 communicates. The chamber or conduit D, which 10 establishes communication between the chamber A and the pipe or line E through which the supply of liquid is drawn, or in which it is desired to create a partial vacuum, is provided with one or more check-valves 7 that open toward the chamber A, one check-valve 7 being preferably arranged at the lower end of the chamber D where it communicates with the chamber A so as to cut off communication between said chambers 15 under certain conditions, and another check-valve 7 being arranged adjacent the upper end of the chamber D where the supply pipe E is connected to same.

Communication is established between the chambers B and D by means of a pipe or conduit 8 in which a valve 9 is arranged, and means is provided for permitting air to escape from the pump suction pipe 3 and from the chamber A into the upper portion of 20 the chamber B, the means that I prefer to use for this purpose consisting of an air-pipe 10 that communicates with orifices 11, 12 and 13 in the pump-suction pipe 3 in the chamber A and in the chamber B, respectively, and provided with a check-valve 14, as shown in dotted lines in the drawings that prevents air, gas or liquid from escaping from the chamber B into said air-pipe 10.

When the apparatus above-described is 25 combined with a rotary or centrifugal pump that is to be used for drawing liquid from a source of supply S and pumping it to the point where it is consumed or utilized, the end of the supply pipe E is submerged in 30 the supply of liquid S and a sufficient quantity of liquid is introduced into the chamber B through a filling opening 15 or through the discharge opening 5 in the top thereof to fill said chamber, the chamber A, the pump C, and the suction and discharge pipes 3 and 4, respectively, of the pump, the liquid flowing into the air-pipe 10 through the orifice 12 in the chamber A. This liquid that is introduced into the apparatus primes the 35 pump, and when the pump is started the liquid in the chamber A will be sucked or drawn out by the pump and forced through the discharge pipe 4 into the upper chamber B, thus causing an equal amount of liquid to 40 be forced out of said chamber B through the

discharge pipe 6. While the pump is drawing the liquid out of the chamber A, liquid is flowing from the chamber B into the chamber A through the bypass or duct 1, but, because of the relatively greater volumetric capacity of the pump as compared to that of said bypass, the pump draws a greater quantity of liquid from the chamber A than can enter it through said bypass during a corresponding period, therefore a 45 partial vacuum or diminution of pressure results in chamber A, conduit D and pipe or line E causing the supply of liquid S to enter the submerged end of the supply pipe E and fill same to a greater or less degree according to the cubical capacity of the pipe E and the conduit D with which it communicates, the liquid continuing to rise in the pipe E until the pressure in the chamber A exceeds the pressure in the chamber or conduit D and in the pipe E by reason of the liquid flowing into the chamber A from the chamber B, the check-valves 7 at each end of the chamber D closing automatically and thus cutting off communication between the chambers D and A. When the liquid in the chamber A is exhausted to a point where the intake end of the suction pipe 3 of the pump is no longer submerged, air enters the pump and thus causes it to become air-bound or cease to 50 pump the liquid through the discharge pipe 4, the liquid in the air-pipe 10 having also been drawn out of same through the orifice 11. The liquid continues to flow into the chamber A from the chamber B until the 55 level of the liquid in the chamber A and in the suction pipe 3 of the pump reaches the orifices 12 and 11 in said chamber and pipe, respectively, that communicate with the air-pipe 10, the air in said chamber and suction pipe 3 escaping through the air-line 10 into the upper portion of the chamber B. At this time the upper chamber B is only partially filled with liquid owing to the fact that when the pump first started an amount 60 of liquid equal to the cubical contents of the chamber A was forced out of the chamber B through the discharge pipe 6, but as soon as the liquid rises high enough in the chamber A and in the suction pipe 3 of the pump to cover the orifices 12 and 11, the pump will be again primed and consequently will resume the pumping of the liquid through the discharge pipe 4 leading from the pump to the chamber B, the check-valve 14 in the 65 upper end of the air-line 10 preventing air from flowing from the chamber B into chamber A and into the suction pipe of the pump. The liquid that has flowed into the chamber A from the chamber B will be sucked or 70 pumped out of said chamber A through the suction pipe 3 and a partial vacuum will again be created in the chamber A and in the chamber D, thereby causing the liquid from the source of supply S to rise higher in the pipe 75

E or to be drawn into the chamber D, depending, of course, upon the length of the supply-pipe E. If the apparatus is located some distance from the source of liquid supply S, several cycles will occur before the supply of liquid in the pipe E reaches the chamber A; or, in other words, if the pipe E is very long a number of charges will be drawn out of the chamber A, thus creating a partial vacuum in said chamber several times before the liquid from the source of supply reaches the chamber A. As soon, however, as the liquid from the source of supply has filled the chamber D and has passed from said chamber into the chamber A the pump C will discharge liquid continuously through the pipe 4, the quantity of liquid which is drawn through the supply pipe E being greater or less according to the quantity of liquid that flows from the chamber B into the chamber A through the bypass 1, it being possible to regulate the flow of the liquid through the bypass 1 by adjusting the valve 2. After the flow of liquid becomes continuous the valve 2 can be closed if desired so as to cut off the passage of the liquid from the chamber B to the chamber A, thereby causing the pump to draw the same quantity of liquid through the supply pipe E that is forced out of the apparatus through the discharge pipe 6.

The air-line 10 not only permits air to escape from the chamber A and from the intake pipe or suction pipe 3 of the pump when the liquid is flowing from the chamber B into said members to prime the pump, but said air-line also equals the pressure in the intake pipe 3 of the pump while the liquid is rising in the pipe 3, thereby eliminating the possibility of the liquid being drawn up into the pump until the chamber A has been filled. Referring to the drawing it will be seen that the lower portion of the air-line or pipe 10 which extends or lies between the orifices 11 and 12, is substantially U-shaped so that it virtually forms a trap. Consequently, after the pump has drawn a charge of liquid out of the chamber A and has become air-bound in the manner previously described, it will be impossible for the pump to again resume pumping of the liquid through the discharge pipe 4 because the air in the U-shaped portion of the air-line 10 causes the pump to remain air-bound until the liquid rises high enough in the chamber A and in the pump-suction pipe 3 to submerge the orifices 11 and 12 which communicate with the air-pipe 10. In case the check-valves in the chamber D leak, the liquid contained in the entire apparatus, line D and liquid which may be contained in pipe 6 will gradually flow into the source of supply S when the pump C is not in motion, if the source of supply S is located at a lower level than the top of chamber B.

The function of the connection or pipe 8 that leads from the chamber B to the chamber D is to prevent all of the liquid in chamber B from flowing into chamber A and being siphoned through the chamber D and line E into the source of supply S when the pump is not in motion in case the check-valves 7 in the chamber D leak. When the level of the liquid in the chamber B falls below the point where the pipe 8 communicates with said chamber, the air in the upper portion of said chamber flows through the pipe 8 into the chamber D and thus destroys any partial vacuum in the chamber D caused by the static column of water between the chamber or conduit D and the source of supply S, thereby eliminating the possibility of the liquid being siphoned out of the chamber B below the point where the connection or pipe 8 is attached in case the valves 7 in the chamber D leak. This pipe 8 determines the lowest liquid level in the chamber B, and it is so arranged that it will always be submerged when the pump is pumping liquid through the discharge pipe 4. Consequently, there is no possibility of air passing from the chamber B into the chamber D through the pipe 8, the quantity of water which passes through the pipe 8 when the pump is operating being regulated by the valve 9.

While I have herein shown only a manually-operated means for regulating the valve 2 in the bypass 1, it will, of course, be understood that an automatic mechanism could be employed for closing said valve when the pump is forcing liquid through the discharge pipe 4 and for opening said valve when the flow of liquid through said discharge pipe ceases.

My improved priming apparatus is not only adapted for use with a pump that is used for pumping a liquid from a source of supply, but it also makes it possible to use a centrifugal or rotary pump for exhausting air or gases from a line or for decreasing the pressure in a closed vessel. When used for this purpose the liquid will be drawn intermittently from the chamber A so as to reduce the pressure in said chamber or create a partial vacuum in same intermittently, the liquid that is drawn out of the chamber A and forced into the chamber B flowing back into the chamber A so as to prime the pump intermittently.

The particular construction of the apparatus is immaterial, so far as my broad idea is concerned, and while I have herein shown the chambers A, B and D integrally connected together or combined in a single casting, it will, of course, be understood that these chambers could be formed by separate members and arranged in various other ways than herein shown without departing from the spirit of my invention.

Having thus described my invention, what I claim as new and desire to secure by Letters Patent is:

1. An apparatus for the purpose described, comprising a chamber adapted to be arranged in communication with a liquid supply line, or a vacuum line, a pump for drawing liquid out of said chamber so as to reduce the pressure in same, and means separate and distinct from the pump for causing liquid to flow into said chamber so as to prime the pump while it is in motion after it has become air or gas-bound.
2. An apparatus for the purpose described, comprising a chamber adapted to be arranged in communication with a liquid supply line or a vacuum line, a pump for drawing liquid out of said chamber so as to reduce the pressure in same, means separate and distinct from the pump for holding a supply of liquid, and means for causing liquid from said source of supply to enter said chamber at a lesser quantity per minute than the capacity of the pump so as to prime the pump while it is in motion after it has become air or gas-bound.
3. An apparatus for the purpose described, comprising a chamber adapted to be arranged in communication with a liquid supply line or a vacuum line, a pump for drawing liquid out of said chamber so as to reduce the pressure in same, and a passageway for establishing communication between said chamber and a supply of liquid that is separate and distinct from the liquid in the pump, the volumetric capacity of the pump being relatively greater than that of said passageway.
4. An apparatus for the purpose described comprising a chamber having an inlet, a check-valve for said inlet, a pump suction pipe terminating inside of said chamber, and a fluid duct or conduit communicating with said chamber for supplying a fluid to said chamber, the cross sectional area of said fluid supply duct being less than the cross sectional area of the pump suction pipe.
5. An apparatus for the purpose described comprising two chambers arranged at different levels, a pump suction pipe terminating inside of the lower chamber, a pump discharge pipe communicating with the upper chamber, and means for permitting liquid to flow from the upper chamber into the lower chamber so as to prime the pump while it is in motion after the pump has sucked the liquid out of the lower chamber to create a partial vacuum in said chamber, said lower chamber being adapted to communicate with a liquid supply line or a vacuum line.
6. An apparatus for the purpose described comprising an upper and a lower chamber, a pump-suction pipe communicating with the lower chamber, a pump discharge pipe

communicating with the upper chamber, means for permitting liquid to pass from the upper chamber into the lower chamber so as to prime the pump while it is in motion, and means for permitting air to escape from said lower chamber and from the pump-suction pipe when said members are being filled with liquid.

7. An apparatus for the purpose described comprising a chamber adapted to be arranged in communication with a liquid supply line or a vacuum line, a pump suction pipe communicating with said chamber for drawing liquid out of said chamber so as to reduce the pressure in same, means for causing liquid to enter said chamber so as to prime the pump while it is in motion when it becomes air or gas-bound, and means for preventing the pump from starting to pump liquid until a certain quantity of liquid has entered said chamber.

8. An apparatus for the purpose described comprising an upper and a lower chamber, a pump-suction pipe terminating inside of said lower chamber, a pump discharge pipe communicating with the upper chamber, means for permitting a liquid to flow from the upper chamber into the lower chamber at a lesser relative volume than that at which the liquid is sucked out of said lower chamber by the pump in the same interval, a valved admission port that establishes communication between said lower chamber and a liquid supply line or vacuum line, and an air-pipe communicating with orifices in said chamber and in the pump suction pipe.

9. An apparatus for the purpose described comprising an upper chamber and a lower chamber, a pump-suction pipe terminating inside of the lower chamber, a pump discharge pipe communicating with the upper chamber, a conduit establishing communication between said lower chamber and a liquid supply pipe or vacuum pipe, a check-valve in said conduit that opens toward said lower chamber, means for permitting liquid to flow from the upper chamber to the lower chamber, and an air trap that establishes communication between the upper portion of the lower chamber and the pump suction pipe adjacent the point where said pipe enters the pump.

10. An apparatus for the purpose described comprising an upper chamber and a lower chamber, a pump-suction pipe terminating inside of the lower chamber, a pump discharge pipe communicating with the upper chamber, a conduit establishing communication between said lower chamber, and a liquid supply pipe or vacuum pipe, a check-valve in said conduit that opens toward said lower chamber, means for permitting liquid to flow from the upper chamber to the lower chamber, an air pipe communicating with orifices in said upper and lower

chambers and in the pump-suction pipe, and means for permitting air to escape from said upper chamber into said conduit so as to destroy any partial vacuum in said conduit.

- 5 11. An apparatus for the purpose described comprising an upper chamber, a lower chamber, a pump-suction pipe terminating inside of said lower chamber adjacent the bottom thereof, a pump-discharge pipe communicating with the upper chamber, a conduit that establishes communication between the lower chamber and a liquid supply line or vacuum line, an inwardly opening check-valve for cutting off commun-

nication between said conduit and said lower 15 chamber, a duct through which liquid can flow from said upper chamber into said lower chamber, a valve for controlling the flow of the liquid through said duct, and an air-pipe communicating with orifices in the 20 lower chamber and in the pump suction pipe.
